[57] CLAIM

The ornamental design for a sportscard frame, as shown and described.

DESCRIPTION

FIG. 1 is a front elevational view of a sportscard frame showing my new design, with a portrait in broken line for illustrative purposes only and forming no part of the claimed design;

FIG. 2 is a front elevational view of the sportscard frame;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
